(57) **CLAIM**

The ornamental design for a rotary driving tool, as shown.

DESCRIPTION

FIG. 1 is a right side elevational view of my rotary driving tool showing my new design;

FIG. 2 is a rear elevational view thereof;

FIG. 3 is a front elevational view thereof;

FIG. 4 is a bottom plan view thereof;

FIG. 5 is a top plan view thereof; and,

FIG. 6 is a left side elevational view thereof.
